BUCKLE.

1,384,066.

Specification of Letters Patent. Patented July 12, 1921.

Application filed February 24, 1921. Serial No. 447,461.

To all whom it may concern:

Be it known that we, ERNEST N. HUMPHREY and OEL E. WARDNER, citizens of the United States of America, residing at New Britain, county of Hartford, Connecticut, have invented a new and useful Buckle, of which the following is a specification.

Our invention relates to an improved buckle for belts and the like.

10 The object is to provide a simple, inexpensive and easily assembled structure which will effectively hold a belt in any one of many adjusted positions, and without injury to the belt.

15 In the drawings:—

Figure 1 is a perspective view of the rear side of our buckle in one preferred form.

Fig. 2 is a longitudinal section thereof, the buckle parts being shown in the position 20 in which the belt is released.

Fig. 3 is a similar view, the parts being in the belt gripping position.

Figs. 4, 5, and 6 are perspective views of details.

25 1 represents the front plate or shield portion of the buckle. 2—3 are two rearwardly projecting flanges at the opposite edges of the shield body 1. 4 represents what we may term the belt gripping plate. This plate is provided intermediate its edges with rearwardly projecting ears 5—5. The ears are provided with enlarged openings or elongated slots as shown. 6 is an operating lever which is provided with a cam end 7. At the base of 30 the cam portion are laterally extending pivot lugs or pins 8—8. The side flanges 2—3 are provided with openings to receive the lugs or pins 8—8, and these pins likewise pass through the elongated slots in the ears 5—5.

40 9 represents a fastening means for one end of a belt 10. This fastening means 9 is carried at the end of the lever 6. The free end of the belt, when the lever is thrown back, may be slipped freely through the passage 45 between the plate 4 and the rear surface of the shield 1. When the belt is properly adjusted, the lever 6 is swung from the position shown in Fig. 2 to that shown in Fig. 3. This causes the cam 7 to press against the

50 rear surface of the plate 4, forcing it tightly against the belt 10 so as to clamp it firmly between the two surfaces formed by the plate 4 and the body 1. It will be noted that the body 1 is preferably curved, and it will

also be noted that the plate 4 is normally 55 substantially straight from end to end and flexible. Hence, when the lever 6 is swung into the position shown in Fig. 3, the plate 4 bends or buckles somewhat and tends to put a bight in the belt 10, which assists in 60 holding the same against slippage in the buckle. Obviously, the belt engaging surface of the plate 4, or the belt engaging surface of the body 1, may be somewhat roughened or irregular to assist in holding the 65 belt. We have not shown such surfaces as roughened since that may be accomplished in any well known manner. However, in the present case, the roughness need be but very slight because the surface engagement 70 is of such substantial area that adequate friction is provided with relatively little pressure on the belt at any one point. It will be observed that the plate 4 is suspended in such a way that it may be designated as a 75 floating plate, by which we mean, it is free to tilt in any direction, and therefore when under pressure, will apply its strain upon the belt in such a manner as to avoid undue pressure at any one point, thereby saving 80 the belt from injury. By preference, the ends of the plate 4 are rolled back slightly to avoid any cutting edge which may abrade or injure the surface of the belt. For the best results, we prefer to pivot the lever 6 85 about midway the length of the body flanges, and we also prefer to have the cam 7 engage the floating plate 4 at about midway its length.

What we claim is:—

1. A buckle for belts and the like, comprising a front plate, two opposite rearwardly directed flanges at the edges thereof, a lever mounted between said flanges, a floating belt gripping plate between the lever 95 and the rear face of the front plate, said belt gripping plate being movable into the belt gripping position by said lever and a support for said gripping plate intermediate the length thereof.

90

2. In a buckle for belts and the like, a curved front plate having two rearwardly extending flanges along its opposite edges, a lever pivotally connected to and between said flanges, a cam carried by said lever, a 105 flexible floating belt gripping plate having rearwardly directing ears at two opposite edges, said ears having enlarged openings

100

through which the pivots for the lever freely pass whereby said plate may tilt longitudinally and laterally.

3. A buckle for belts and the like, comprising a front plate curved longitudinally, two rearwardly projecting flanges at the opposite edges of said plate, a lever pivoted between and intermediate the length of said flanges, said lever including a cam end adjacent to the pivotal portion thereof, a flexible floating belt gripping plate having rearwardly directed ears intermediate the length

thereof and at opposite edges, with enlarged passages in said ears through which the pivot ends for the lever pass, with means carried 15 by the lever for holding one end of the belt, the other end of the belt being adapted to be passed between the front plate and the floating plate and to be clamped therebetween when said lever is swung into one position, and to be released when swung into another position.

ERNEST N. HUMPHREY.
OEL E. WARDNER.
